SPRAY DRIED DETERGENT COMPOSITION

Edgar E. Ruff, Bergenfield, N.J., assignor to Lever Brothers Company, New York, N.Y., a corporation of Maine

No Drawing. Filed May 9, 1955, Ser. No. 507,133

8 Claims. (Cl. 252—109)

The present invention relates to a detergent composition, and more particularly to a spray dried detergent composition containing soap.

In the production of spray dried detergent compositions containing nonionics as the active components, the nonionic surfactants frequently tend to separate out in the crutcher or in the relay storage tank used to insure continuous feed to the spray drying tower. Such separation causes the spray dried compositions to be nonuniform. Furthermore, the heterogeneity of the separated slurry as it passes through the tower nozzles results in the formation of many dense masses containing insufficient nonionic surfactant to provide the necessary particle expansion, thereby resulting in a product having an undesirably high specific gravity.

These difficulties as well as others discussed below have been overcome by the inclusion of a small amount of soap in the low sudsing spray dried nonionic detergent composition of the present invention.

The composition of the present invention comprises from about 5% to about 15% by weight of the nonionic surfactants Pluronic L-64 plus Oronite Dispersant NIW. Preferably, the composition contains about 10% of Pluronic L-64 and about 1% of Oronite Dispersant NIW. Pluronic L-64 is a compound having the empirical formula $\text{HO}-(\text{C}_2\text{H}_4\text{O})_a(\text{C}_3\text{H}_6\text{O})_b(\text{C}_2\text{H}_4\text{O})_c\text{H}$ prepared by condensing ethylene oxide with a hydrophobic base formed by the condensation of propylene oxide with propylene glycol where b is 26-30. The molecular weight of the base unit $(\text{C}_3\text{H}_6\text{O})_b$ is about 1501 to 1800 and a plus c is an integer such that the molecule contains from 40% to 50% ethylene oxide. Oronite Dispersant NIW is a polypropylene alkyl phenol averaging tetradecyl in the alkyl radical condensed with ethylene oxide to an average of 9 ethylene oxide groups.

The composition also contains from about 0.2% to about 2.0% by weight of a soap which is a salt of one or more of the saturated or unsaturated fatty acids having an acyl group of from about 8 to about 22 carbon atoms with an alkali metal, such as sodium, and may include, for example, the alkali metal salts of myristic acid, palmitic acid, tallow fatty acids and coconut oil fatty acids.

The composition also contains an amount up to about 10% water, preferably about 4%, as well as a builder, such as, pentasodium tripolyphosphate, and water-soluble supplemental builders, such as, sodium carbonate, or other alkaline inorganic salts, sodium silicate, and sodium sulfate. From about 20% to about 50% by weight of pentasodium tripolyphosphate may be employed although about 39% thereof is preferred. The sodium carbonate or other alkaline inorganic salt content, to supply an alkali reserve in washing operations of the composition may vary from about 10% to about 20% by weight, about 17% being preferred.

Sodium silicate is used for its well known property of lessening the extent of corrosion of the metals commonly exposed to a solution of the detergent composition in washing appliances. It is preferred to limit this compo-

2

nent to an amount effective for the aforementioned purpose, but which is at the same time not so high that excessively cloudy washing solutions are obtained. Pick-up carbon dioxide from the atmosphere during trade storage of products containing silicates tends to cause formation of free silica, which is insoluble in water and forms cloudy solutions. From about 5% to about 15% by weight of sodium silicate may be employed, about 11% being preferred. It is also preferred to use the more alkaline soluble silicates, such as, for example, those having SiO_2 to Na_2O ratios of 2.4 to 1 or 2.0 to 1.

The neutral salt filler, sodium sulfate, makes up essentially the balance of the composition, although the detergent composition may contain minor proportions of a dye and salts of carboxymethyl cellulose or carboxymethyl hydroxyethyl cellulose. About 0.5% of sodium carboxymethyl hydroxyethyl cellulose is generally added to the composition. Generally about 0.05% of a fluorescent dye, such as the disodium salt of 4,4'-bis(4-phenylamino)-2,2'-stilbene disulfonic acid, may be added to the composition.

The spray dried detergent composition is prepared by mixing the components thereof in an aqueous slurry in a crutcher for about 30 minutes. The aqueous slurry has a low water content, i.e., from about 12% to about 20% and a relatively high temperature of about 185° F. The actual water used is selected at as low a level as may be possible consistent with obtaining a pumpable viscous crutcher mix using any particular combination of desired inorganic builders and fillers. The slurry is then pumped to a relay storage tank from which it is continuously fed into a spray drying tower having an air inlet temperature of about 490° F. In the tower the composition is spray dried to a free flowing powder having a moisture content below about 10%, and preferably about 4%, and a specific gravity of not more than about 0.4 g./cc., and preferably about 0.3 g./cc.

The presence of soap in the detergent composition prevents the components thereof from separating out in the crutcher or in the relay storage tank having slow moving agitators by apparently exerting an emulsifying action thereon. Hence the spray dried detergent composition is uniform and free flowing. Moreover, the presence of soap in the detergent composition enables the specific gravity of the composition to be controlled, since it was found that an increase in the soap content produced a decrease in the specific gravity of the spray dried product. A microscopic examination of the particles of the spray dried product showed that as the soap content of the detergent composition was increased the particles of the spray dried product became more puffed and hence were lighter and had a lower specific gravity.

Data showing these properties of the detergent composition due to the presence of soap therein is given below in Examples 1-5 of Table I wherein the amounts of the components of the composition are given as percentages by weight on a dry basis. The detergent composition in Example 1 does not contain soap while the compositions in Examples 2-5 contain increasing amounts of soap with the amounts of the other components remaining constant except for a decrease in the sodium sulfate content corresponding to the increase in the soap content.

It can be readily seen that in Example 1 wherein the detergent composition did not contain soap that the aqueous slurry was heterogeneous and that the spray dried product was nonuniform and had too high a specific gravity. In examples 2-5, however, wherein soap was added to the composition the aqueous slurry was homogeneous and the spray dried product was uniform and had a low specific gravity which could be readily controlled.

The nonionic surfactants, Pluronic L-64 and Oronite Dispersant NIW, and detergent compositions containing

TABLE I

Example No.	1	2	3	4	5
Pluronic L-64	9.72	9.72	9.72	9.72	9.72
Oronite Dispersant NIW	1.39	1.39	1.39	1.39	1.39
Pentasodium Tripolyphosphate	38.89	38.89	38.89	38.89	38.89
Sodium Carbonate	16.67	16.67	16.67	16.67	16.67
Sodium Silicate	11.11	11.11	11.11	11.11	11.11
Sodium Carboxymethyl Hydroxyethyl Cellulose	0.55	0.55	0.55	0.55	0.55
Anhydrous Sodium Tallow Soap	0.27	0.27	0.27	0.27	0.27
Sodium Sulfate	21.62	21.35	21.07	20.51	19.42
Fluorescent Dye	0.05	0.05	0.05	0.05	0.05
Total	100	100	100	100	100
Operating Data:					
Water Content of Slurry	20%	20%	20%	20%	20%
Slurry Temperature	185° F.	185° F.	185° F.	185° F.	185° F.
Tower Air Inlet Temperature	490° F.	490° F.	490° F.	490° F.	490° F.
Mixing Time in Crutcher	30 min.	30 min.	30 min.	30 min.	30 min.

Characteristics of Final Product	Free flowing, non-uniform.	Free flowing, uniform.	Free flowing, uniform.	Free flowing, uniform.	Free flowing, uniform.

¹ The disodium salt of 4,4'-bis (4-phenylamino-6-(bis(2-hydroxyethyl)) amino-s-triazine-2-ylamino)-2,2' stilbene disulfonic acid.

them are sufficiently soluble in water at lower temperatures such as 120° F. to about 140° F., to produce substantially clear solutions at typical usage concentration. They are, however, less soluble in both hard and soft water at higher temperatures used in washing, such as about 140° F. to 190° F., so that these nonionics separate from such heated solutions as suspended minute droplets forming turbid solutions. This is clearly illustrated by the following Examples 6-8 wherein the percentages are by weight.

Example 6

One liter of distilled water was added to 3.0 grams of the following spray dried detergent composition and the resulting solution heated and observations made of the turbidity thereof.

	Percent
Pluronic L-64	8.75
Oronite Dispersant NIW	1.25
Pentasodium tripolyphosphate	35
Sodium carbonate	15
Sodium silicate	10
Sodium carboxymethyl hydroxyethyl cellulose	0.5
Water	10
Fluorescent dye (same as in Example 1)	0.03
Sodium sulfate	19.47
Total	100

The observations of the turbidity of this solution as it was heated and subsequently cooled were as follows:

- 120° F.—Faintly hazy; some undissolved particles.
 130° F.-140° F.—Slightly more hazy than at 120° F.
 160° F.—Slightly turbid; printing could be read through 100 mm. of the solution.
 170° F.—Turbid; printing could be read through 100 mm. of the solution.
 174° F.—More turbid; printing could not be read through 100 mm. of the solution, but objects could be discerned.
 180° F.—Very turbid; objects could not be seen through 100 mm. of the solution.
 190° F.—Slightly more turbid than at 180° F.
 180° F. down to 150° F.—Turbid; printing could not be read through 100 mm. of the solution, but objects could be discerned.
 140° F. down to 130° F.—Slightly clearer than at 150° F., but still turbid; printing could not be read through 100 mm. of the solution, but objects could be discerned.
 120° F.—Much clearer than at 130° F.; printing could be read through 100 mm. of the solution.

25 118° F.—Much clearer than at 130° F.; only slightly turbid.

113° F.—Clear.

To substantiate that it was the nonionic detergents in the composition of Example 6 which were separating from solution and producing the turbidity, the following tests and observations were made, Pluronic L-64 being tested in Example 7 and Oronite Dispersant NIW in Example 8.

Example 7

35 One liter of distilled water was added to 0.26 gram of Pluronic L-64 (the amount of Pluronic L-64 in 3 grams of the composition in Example 6) and the mixture heated and subsequently cooled. Observations were made as to the turbidity of the resulting solution.

40 130° F.—Turbid.

140° F.-180° F.—Progressively more turbid as the solution was heated; printing could be read through 100 mm. of the solution.

45 190° F.—Very turbid; printing could not be read through 100 mm. of the solution, but objects could be discerned.

180° F.—Very turbid; printing could not be read through 100 mm. of the solution, but objects could be discerned.

170° F.—Slightly clearer than at 180° F.; printing could be read through 100 mm. of the solution.

160° F. down to 130° F.—Progressively clearer as the solution cooled; only a faint haze at 130° F.

120° F.—Clearer than at 130° F.; barely noticeable haze.

105° F.—Clear.

Example 8

60 One liter of distilled water was added to 0.04 gram of Oronite Dispersant NIW (the amount of Oronite Dispersant NIW present in 3 grams of the composition in Example 6) and the mixture heated and subsequently cooled. Observations were made as to the turbidity of the resulting solution.

130° F.—Clear.

140° F.-160° F.—Faint haze.

65 160° F.-190° F.—Slightly more haze than at 150° F.

180° F. down to 120° F.—Progressively clearer as the solution cooled; at 120° F. the solution was almost perfectly clear; only a barely noticeable haze was evident.

70 85° F.—Same as when at 120° F.

75 The turbidity observed in the above example is a separation which is similar to the separation existing in plant slurries in the absence of extraordinary violent agitation except that in plant operations when soap is

not used there is not only separation of minute particles but layers of separate ingredients can be observed resulting in objectionable nonuniformity of the slurry and the spray dried product.

Solubilization by surface-active agents, such as soap, is a well known phenomenon known to occur at concentrations of the solubilizing agent at or above a critical level known as the "critical concentration for the formation of micelles" or more commonly as the "critical micelle concentration." Above this level, agglomerates of more or less definitely oriented molecules are known to exist in solutions of surface-active agents. Such agglomerates are called "micelles," and they have a solubilizing effect on many substances not soluble in water alone or in solutions of surfactants at concentrations below the critical level. Contrariwise, however, a small proportion of a soap in the composition of Example 6, namely about 0.5% to about 2.0% by weight of the total detergent composition and being well below the critical micelle concentration at washing concentrations of the detergent, had a solubilizing effect on the nonionics in either hard or soft water. This is demonstrated by the following Examples 9-12.

Example 9

0.015 gram (0.5% by weight of the total composition) of sodium tallow soap were mixed with 3.0 grams of the composition in Example 6 contained in one liter of distilled water and the mixture heated. Observations were made as to the turbidity of the solution.

120° F.-160° F.—Clear.

180° F.-190° F.—Very slightly hazy; printing could be read easily through the solution.

Example 10

One liter of water having a hardness of 180 parts per million was added to a mixture of 3 grams of the composition of Example 6 containing 0.015 gram of sodium tallow soap (0.5% by weight of the total composition) and the mixtures heated. Observations were made as to the turbidity of the resulting solution.

120° F.—Very slight haze; some undissolved particles.

140° F.—Slightly clearer than at 120° F.

150° F.-170° F.—Same as at 140° F.

180° F.—Just slightly more haze than at 170° F.

190° F.—Same as when at 180° F.; printing could easily be read through 100 mm. of the solution.

Example 11

0.015 gram of sodium myristate (0.5% by weight of the total composition) were added to 3 grams of the composition in Example 6 contained in one liter of distilled water and the solution heated to 177° F. Observations of the solution during heating showed that the turbidity of the solution was considerably less than the values shown for the corresponding temperature recordings in Example 6. This level of 0.015 gram per liter is well below the critical micelle concentration for sodium myristate, which has an accepted value of approximately 1.5 grams per liter.

Example 12

0.015 gram of sodium palmitate (0.5% by weight of the total composition) was added to 3 grams of the composition in Example 6 contained in one liter of distilled water and the solution heated to 177° F. Observations of the solution during heating showed that the turbidity of the solution was considerably less than the values shown for the corresponding temperature recording in Example 6. This amount, 0.015 gram per liter, of sodium palmitate is also lower than that corresponding to the accepted critical micelle concentration of approximately 0.11 gram per liter.

The data in Examples 9-12 thus readily show that the addition of about 0.5% by weight of the total com-

position of a soap to the detergent composition containing the nonionics shown in Example 6 substantially prevents the separation of the nonionic surfactants from solutions of the composition at washing temperatures in either hard or soft water.

Various modifications and changes may be made in the compositions of this invention without departing from the spirit of the invention or sacrificing any of the advantages thereof. The invention, therefore, is to be limited only within the scope of the appended claims.

I claim:

1. A spray dried detergent composition comprising from about 5% to about 15% of (1) a compound having the empirical formula

prepared by condensing ethylene oxide with a hydrophobic base formed by the condensation of propylene oxide with propylene glycol where b is an integer selected from the group consisting of 26 to 30 and a plus c is an integer such that the molecule contains from 40% to 50% ethylene oxide, and (2) a polypropylene alkyl phenol averaging tetradecyl in the alkyl radical condensed with ethylene oxide to an average of 9 ethylene oxide groups; from about 20% to about 50% of pentasodium tripolyphosphate; from about 10% to about 20% of sodium carbonate; from about 5% to about 15% of sodium silicate; from about 0.2% to about 2.0% by weight of a water-soluble alkali metal salt of a fatty acid having an acyl group of from about 8 to about 22 carbon atoms; an amount up to about 10% water; and the balance essentially sodium sulfate, the above amounts being expressed as percentages by weight on a dry basis with the exception of water.

2. A spray dried detergent composition as set forth in claim 1 containing about 0.5% sodium carboxymethyl hydroxyethyl cellulose and about 0.05% of a fluorescent dye.

3. A spray dried detergent composition comprising about 10% of a compound having the empirical formula

prepared by condensing ethylene oxide with a hydrophobic base formed by the condensation of propylene oxide with propylene glycol where b is an integer selected from the group consisting of 26 to 30 and a plus c is an integer such that the molecule contains from 40% to 50% ethylene oxide; about 1% of a polypropylene alkyl phenol averaging tetradecyl in the alkyl radical condensed with ethylene oxide to an average of 9 ethylene oxide groups; from about 20% to about 50% by weight of pentasodium tripolyphosphate; from about 10% to about 20% by weight of sodium carbonate; from about 5% to about 15% by weight of sodium silicate; from about 0.2% to about 2.0% of a water-soluble alkali metal salt of a fatty acid having an acyl group of from about 8 to about 22 carbon atoms; an amount up to about 10% water; and the balance essentially sodium sulfate, the above amounts being expressed as percentages by weight on a dry basis with the exception of water.

4. A spray dried detergent composition comprising about 10% of a compound having the empirical formula

prepared by condensing ethylene oxide with a hydrophobic base formed by the condensation of propylene oxide with propylene glycol where b is an integer selected from the group consisting of 26 to 30 and a plus c is an integer such that the molecule contains from 40% to 50% ethylene oxide; about 1% of a polypropylene alkyl phenol averaging tetradecyl in the alkyl radical condensed with ethylene oxide to an average of 9 ethylene oxide groups; about 39% of pentasodium tripolyphosphate; about 17% of sodium carbonate; about 11% of sodium silicate; from about 0.2% to about 2.0% of a water-soluble alkali metal salt of a fatty acid having an acyl

group of from about 8 to about 22 carbon atoms; about 4% of water; and the balance essentially sodium sulfate, the above amounts being expressed as percentages by weight on a dry basis with the exception of water.

5. A spray dried detergent composition as set forth in claim 4 wherein the water-soluble alkali metal salt of a fatty acid is sodium tallow soap.

6. A spray dried detergent composition as set forth in claim 4 wherein the water-soluble alkali metal salt of a fatty acid is sodium palmitate.

7. A spray dried detergent composition as set forth in claim 4 wherein the water-soluble alkali metal salt of a fatty acid is sodium myristate.

8. A spray dried detergent composition as set forth

in claim 4 containing about 0.5% sodium carboxymethyl hydroxyethyl cellulose and about 0.05% of a fluorescent dye.
